UNITED STATES PATENT OFFICE.

EARLE I. STAPLES, OF NEW YORK, N. Y.

LIQUID-FUEL BURNER.

Application filed March 31, 1923. Serial No. 629,075.

To all whom it may concern:

Be it known that I, EARLE I. STAPLES, a citizen of the United States, residing at New York city, in the county of New York and State of New York, have invented new and useful Improvements in Liquid-Fuel Burners (Case B), of which the following is a specification.

This invention relates to liquid fuel burners and particularly to means or atomizing the mixture employed in burners of this type, and has for its primary object the provision of means for super-heating, pulverizing and vaporizing steam and oil into an oil gas of the highest efficiency. While I refer to the use of oil and steam in connection with the burner, this is simply illustrated, and it shall be understood that air as an atomizing agent can be used in all types of boilers, furnaces, retorts, kilns, heaters, etc.

A further object of the invention is to provide a burner having means for rendering the burner self cleaning, thus eliminating the necessity of removing the burner from its connection.

A still further object of the invention is to provide a burner having an oil mixer and a mixer for steam or air, the latter being designed to impel a mist of steam or air in an atomized state to a mixing chamber and the former being correspondingly designed to deliver a mist of oil to said chamber in the direct path or course of travel of air or steam passing from said steam or air mixer, and the two said mixers co-acting to thoroughly super-heat, atomize and vaporize the mixture and cause it to be finally discharged in relatively equalized volumes from the tip of the burner.

With these and other objects in view, the invention resides in certain novel construction and combination and arrangement of parts, the essential features of which are hereinafter fully described, are particularly pointed out in the appended claim, and are illustrated in the accompanying drawing, in which:

Figure 1 is a longitudinal section through the burner showing parts in elevation.

Figure 2 is a side elevation of the companion mixers.

Figure 3 is a view looking toward one end of the mixer structure.

Figure 4 is a similar view of the opposite end of the mixer structure.

Figure 5 is a vertical longitudinal section through the bushing.

Figure 6 is an end view of the bushing.

Figure 7 is a section taken approximately 60 on line 7-7 of Figure 1, the valve being omitted.

Figure 8 is a section through a modified form of tip.

Figure 9 are detail views of the washer. 65

Figure 10 is a transverse section through the valve.

In carrying the invention into practice, I employ a valve casing or body 10 divided by diaphragms or parting walls 11 to provide non-communicating spaces 12 and 13, the latter being connected with a union 14 adapted to be connected in any suitable customary manner with an oil feed pipe. The space 11 is connected with a similar 75 union 15 adapted to be connected with a pipe for the admission to the burner of steam or compressed air.

The body 10 is provided with a hollow cylindrical valve seat 16 with which a substantially cylindrical valve 17 co-acts. This valve is provided with a V-shaped port 18 at one side, the walls of which are beveled to produce knife edges 19. The valve 17 is provided with a stem 20 which passes 85 through a stuffing box 21 on one end of a bonnet 22. This bonnet is interiorly threaded to accommodate the thread 23 of the valve stem. In this manner the valve 17 can be moved in the bore 24 of the seat 90 16 or adjusted with respect thereto so that requisite portions of the port 18 can be respectively covered and uncovered. The valve 17 operates in a portion of the space 13 so that the oil entering said space is free 95 to pass over the knife edges 19 and through the port 18 where it will be delivered to mixing end of the burner in a manner to be hereinafter explained. The valve stem 20 is provided at one end with a suitable hand 100 wheel 25, and at the juncture of the stem with the valve 17, a circular collar 17^a is formed and adapted to fully close against a circular wall 17^b of the seat 16.

Connected with the body 10 in communication with the space 12 is a steam or air pipe 26, the same adapted to act as a conduit for the passage of air or steam from the union 15 to the tip of the burner. By causing the steam to flow around the oil 110 pipe 29, the oil is superheated before passing to the mixing chamber of the burner.

The opposite end of the pipe 26 has connection with a sleeve 27 which in turn, is threadedly connected with a bushing 28.

Connected at one of its ends to the seat 5 16 is an oil pipe 29, the opposite end of which is threadedly connected in the bore 30 of a mixer structure 31. This structure 31 comprises a mixer or head 32 of cylindrical formation of a proportion to snugly 10 fit within a part of the sleeve 27 and a mixer 32^a which extends through an aperture 34 in the forward end of the aforesaid bushing 28. The mixer 32 is provided with peripheral spiral slots 35 which open re- 15 spectively toward the opposite ends of the sleeve 27. The mixer 32 is also formed with spirally milled horizontal slots 36. These mixers 32 and 32^a are positioned with respect to each other and in the sleeve 27 and 20 bushing 28 whereby they define with the walls thereof a mixing or atomizing chamber 36. Said mixers 32 and 32^a are joined together by a portion 37 having radial apertures 38 of relatively small proportion. The 25 end of the mixer structure 31 beyond the mixer 32 is closed by a suitable member 38.

The tip 39 is in the form of a hollow body removably connected at 40 to the forward end of the bushing 28. This tip has 30 perforated cast washers 42 arranged therein so as to deflect oil and steam vapor gas equally to the top and bottom slots 43 and 44 in the front of the tip. These slots 43 and 44 are milled so as to be disposed in 35 a plane parallel to the longitudinal axis of said tip. As stated, the mixer 32 passes through the aperture 34 in the forward end of the bushing 28 and as clearly shown in Figure 6, it will be observed that said 40 mixer is disposed slightly below the longitudinal center of the tip 39, whereby to allow the oil and steam gas to emerge with proper flow through the apertures in the washers 42, causing the flow to be equalized 45 in equal volume to each of the aforesaid slots 43 and 44. Around the mixer 32^a and formed in the front wall of the bushing 28 is a circular series of small apertures 45 which open at one side to the burner tip 50 and at the opposite side to the atomizing or mixing chamber defined by the spacing of the mixers 32 and 32^a and their relation to the internal walls of sleeve 27 and bushing 28.

55 In operation, steam or compressed air enters the top union 15 and flows by way of the space 12 into the pipe 16, then through mixer 32 whose slots or grooves 35 act to place the steam in centrifugal motion 60 and correspondingly move the steam while in this motion and in a pulverized state through the mixing and atomizing chamber in front of said mixer 32. This wire draws the steam and sets actual amount of atomizing steam from boiler. Oil passes through

the port 18 in the valve 17 and enters the pipe 27 where it is permitted to flow to the connection 37. From this connection the oil in a finely atomized state or in mist form is scattered in radial directions in the mixing chamber and in the direct path or course of the atomized steam as it whirls through said chamber on its passage from the mixer 32. Incident to this manner of combining the oil with steam in centrifugal motion, the atoms of oil are thoroughly disintegrated and combined in a highly atomized state with the steam or air as the case may be. The mixture then proceeds through the apertures 45 and the spiral slots 36 of the mixer 32 so that the oil gas is further pulverized before its actual passage to the burner tip.

Each of the unions 14 and 15 is provided with a suitable strainer A and its function 85 is to prevent sediment or foreign matter from passing into the burner.

In order that the burner can be blown out and cleaned, and in fact rendered self cleaning, I connect the steam or air space 90 12 with a valve B at one side of the body 10. This valve co-acts with a by-pass C between the space 13 and the chamber D of said valve B. An aperture E is formed in one wall of the chamber D to co-act 95 with the valve stem F and as illustrated this aperture opens to the oil space 11 so that when the opening E is uncovered steam or air from the space 11 is free to pass into the by-pass C and escape with considerable 100 pressure against the strainer of the union 14, and through the entire oil pipe 29, mixing chamber 36 and tip 39 thus maintaining a clean condition of the oil inlet and aforesaid parts and permitting the union to be 105 directly opened to a suitable waste receptacle.

In the modified form of my invention illustrated in Figures 8 and 9, the tip 39^a is provided with a single slot 43^a and a 110 co-acting apertured washer 42^a.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claim.

What is claimed as new is:

A liquid fuel burner, a cylindrical chamber having an inlet opening at one end adapted to be arranged in communication 125 with a source of steam or air, a tip arranged upon the outer end of the cylindrical chamber and having a plurality of slots therein, a pair of divergent plates arranged in the tip and disposed in the path of a combust- 130

tible mixture passing through the tubular chamber, the plates having openings therein, a tube arranged in the cylindrical casing and having one end closed and its other 5 end in communication with a source of liquid fuel, and provided with a plurality of outlet openings adjacent its closed end, a circular head carried by the tube intermediate its ends and being of a diameter 10 equal to the diameter of the cylindrical chamber, and provided with a plurality of parallel radial ports in its periphery through which the steam or air passes, an annular element arranged in the cylindrical casing adjacent the tip, and a second head 15 carried by the tube adjacent its closed end and being of a diameter to be received in the bushing and also having radial slots through which the combustible mixture passes to thoroughly mix the latter before 20 it passes into the tip.

In testimony whereof I have affixed my signature.

EARLE I. STAPLES
